UNITED STATES PATENT OFFICE.

HARRY D. LATHROP AND WALTER H. PAULSON, OF CHICAGO, ILLINOIS; SAID PAULSON ASSIGNOR TO SAID LATHROP.

CONVEYER FOR WASHING MACHINES.

Application filed July 31, 1925. Serial No. 47,194.

The invention relates to improvements in washing machines especially adapted for the washing of milk bottles and the like and has for its object the provision of an improved 5 machine of this character which is of simple construction and efficient in operation. Another object of the invention is to provide such a machine having provision therein for automatically feeding the articles to be 10 washed thereto and discharging said articles therefrom.

Other objects will appear hereinafter.

The invention consists in the combinations and arrangements of parts hereinafter described and claimed.

The invention will be best understood by reference to the accompanying drawings, forming a part of this specification, and in which,

20 Fig. 1 is a top plan view of the feed and discharge end of a machine embodying the invention;

Fig. 2 a top plan view of the other end of the machine;

25 Fig. 3 a section taken substantially on line 3—3 of Fig. 2;

Fig. 4 an end view of the machine;

Fig. 5 a side view of one side of the feed and discharge end of the machine;

30 Fig. 6 a side view of other side of the feed and discharge end of the machine;

Fig. 7 a horizontal section taken on line 7—7 of Fig. 5;

Fig. 8 a vertical section taken on line 8—8 35 of Fig. 5;

Fig. 9 a vertical section taken on line 9—9 of Fig. 5;

Fig. 10 an enlarged vertical transverse section taken through the discharge end of the 40 machine;

Fig. 11 a vertical transverse detail section taken through the feed and discharge mechanism of the machine; and

Fig. 12 a detail view of a stop mechanism 45 employed in the machine.

The preferred form of construction as illustrated in the drawings comprises a suitable supporting frame 15 having a horizontally travelling endless chain 16 mounted to 50 travel over horizontal sprocket wheels 17 and 18 secured to the upper ends of vertical shafts 19 and 20. As best shown in Figs. 2 and 3 the shaft 19 is a stud shaft mounted in a block 21 on an adjustable carriage 22 55 adjustable on the frame 15 through a slot

and bolt connection as shown, adjustments of said carriage being effected by a bolt 23 and whereby the chain 16 may be tightened or loosened as desired. As best shown in Fig. 10 the shaft 20 is a driving shaft provided at the top with a bearing 24 located just under the sprocket 18 and at the bottom with an adjustable bearing 25 adjustable in the frame of the machine by means of adjusting bolts 26 and whereby the vertical 60 position of the shaft 20 may be nicely adjusted as desired. The shaft 20 is driven by bevelled gear 27 meshing with a bevelled gear 28 on a countershaft 29 carrying a gear 30 meshing with a gear 31 on another countershaft 32 best shown in Figs. 1, 7 and 10. The shaft 32 carries a gear 33 meshing with a larger gear 34 on a countershaft 35, best shown in Figs. 1, 4, 7 and 9. The shaft 35 carries a gear 36 meshing with a gear 37 on 70 shaft 38 carrying a gear 39 meshing with a gear 40 on shaft 41. Shaft 41 carries a gear 42 meshing with a gear 43 on shaft 44. As best shown in Figs. 8 and 9 the shaft 44 carries a driving pulley 45 connected by a 75 belt 46 with a pulley 47 on an electric motor 48 for driving the machine. As best shown in Fig. 9 the gear 34 is a mutilated gear having teeth on substantially one-third of its periphery and whereby the shaft 32 and consequently the sprocket chain 16 will be intermittently operated, said sprocket chain travelling through substantially one-third of the revolution of gear 34 and remaining stationary during the other two-thirds of 80 said revolution as will be readily understood. As indicated in Fig. 9 the gear 34 is provided with an enlarged tooth 34' at the commencement of the gear teeth thereon and the gear 33 is provided with an enlarged tooth space 85 33' to receive the enlarged tooth 34 and thus facilitate reengagement of the gears 34 and 33 at the commencement of the driving of chain 16.

Guide tracks 49 in the form of angle irons 100 are arranged on the frame 15 to support the chain 16 between the sprockets 17 and 18, and thus prevent sagging of said chain, as best shown in Figs. 1 and 8. As best shown in Figs. 1, 2, 8 and 9 the links of chain 16 105 are provided on their outer sides with outwardly extending supporting lugs 50 fitting between similar lugs 51 on a plurality of bottle holders 52, said bottle holders being pivotally mounted by the bolts 52' on the 110

lugs 50 so as to be capable of swinging downwardly and outwardly with reference to the chain 16. Each of the bottle holders 52 is in the form of an open downwardly tapering frame open at both top and bottom and provided at the bottom with inwardly extending supporting lugs or fingers 53 adapted to support the mouth of an inverted milk bottle in said holder as indicated in dotted lines in Fig. 11. Each of the bottle holders 52 carries on its outer side a roller 54 arranged to travel on an angle iron track surrounding the chain 16 and consisting of straight side portions 55 curved end portions 56 and intermediate depressible portions 57 and 58 arranged on opposite sides of the feed in and discharge end of the machine. The depressible track sections 57 and 58 are provided on their sides with mounting ears or lugs 59 connected by links 60 with rocker arms 61 on two parallel adjacent horizontal rocker shafts 62 and 62' arranged centrally under the chain 16, as best shown in Figs. 1 and 4. The rocker shafts 62 and 62' carry gears 63 meshing with rack bars 64 on a vertically reciprocating bar 65 as best shown in Fig. 4. As best shown in Fig. 10 the bar 65 carries a roller 66 running in a cam groove 67 on a cam drum 68 loose on the shaft 20 and carrying at its bottom a bevel gear 69 meshing with a bevel gear 70 on the constantly driven shaft 35 and whereby said cam drum 68 will be constantly rotated. The form of the cam groove 67 is such that during each pause in the travel of the chain 16 the rack bars 64 will be elevated and depressed to cause depression and elevation of the track portions 57 and 58'. As best shown in Figs. 7, 10 and 12 a shaft 20 carries a stop wheel 71 fixed thereto and provided with four peripheral notches 72 adapted to receive a stop dog 73 on a lever arm 74 arranged to swing in a guide strap 75 on the underside of a reciprocating bent bar 76. The lever 74 carries a roller 77 resting against the inner side of the guide strip 75 and the reciprocating bar 76 carries a roller 78 running on a cam plate 79 provided with a cam surface 80, and fixed to the gear 34 to be operated constantly by the shaft 35. The cam 80 is so arranged or timed as to cause the withdrawal of the dog 73 from notch 72 in the wheel 71 during the intermediate periods of the rotation of shaft 20 and consequent feed of chain 16, but to cause said dog to engage one of said notches during each pause in the feed of said chain thereby holding the chain accurately in position during each pause. As best shown in Figs. 9 and 11 curved guides 81 are arranged under each of the depressible track portions 57 and 58 to guide said depressible track portions during their downward and upward movements as explained above, and the cam groove 67 in the

cam 68 on shaft 20 is so shaped or timed that the depression and elevation of the track sections 57 and 58 will occur simultaneously during the pauses in travel of the chain 16.

As best shown in Figs. 1, 9 and 11 a tiltable rack 82 is mounted on the frame 15 adjacent the corresponding depression track portion 57, said rack being formed of sheet metal and provided with six V-shaped depressions 83 and a supporting ledge 84 at the bottom of said depressions and whereby six milk bottles may be placed on and supported by said rack in substantially upright positions as indicated in Fig. 11. The rack 82 is pivoted to tilt on the trunnions 85 and is provided with rocker arms 86 connected by links 87 with rocker arms 88 on the shaft 62 and whereby at each operation of the rocker shaft 62 the rack 82 will be tilted inwardly and downwardly to invert the bottles and discharge said bottles from said rack under the influence of gravity. The bars are so arranged and timed that the outward tilting of the bottle holders 52 resting on the track portion 57 occurs simultaneously with the tilting of the rack 82 so that each depression 83 is thus brought into registration with a corresponding outwardly and downwardly tilted holder 52 and whereby each bottle is discharged by the influence of gravity and the momentum imparted by the tilting of the rack into a corresponding bottle holder. Immediately thereafter the rack 82 is tilted outwardly into receiving position and the track portion 57 elevated to restore the bottle holders to normal position of travel on the track. In this manner it will be noted that during each pause in the travel of the chain 16 six bottles placed by hand on the rack 83 may be automatically fed into the bottle holders on the chain 16.

As best shown in Figs. 1, 8 and 11, a discharge rack 89 formed of sheet metal and provided with six V-shaped depressions 90 and a supporting ledge 91 is arranged on the opposite side of the machine adjacent and corresponding to the track portion 58. The rack 89 is tiltably supported on trunnions 92 and provided with rocker arms 93 connected by links 94 with rocker arms 95 on the rocker shaft 62'. The arrangement is such that as the track portion 58 is depressed to swing the corresponding bottle holders 52 downwardly and outwardly, the rack 89 is tilted inwardly into registration with said bottle holders as best shown in Fig. 11 and whereby the bottles in said bottle holders are automatically discharged by gravity and momentum into the recesses 90 in said rack 89. Immediately thereafter, and as the bottle holders are restored to position of travel the rack 89 is tilted upwardly and outwardly to free the bottles and discharge the same.

As best shown in Figs. 1, 4 and 11 a slotted endless belt conveyor 96 is arranged im-

mediately outside of the rack 89 to receive the bottles discharged therefrom. A guide plate 96' is arranged along the outer side of the conveyer 96 to hold the bottles thereon.

- 5 As the bottles travel on the conveyer 96 the bevelled ends of the recesses 90 will move said bottles outwardly to free them completely from said rack. As best shown in Figs. 1, 6 and 8 the endless belt conveyer 96 10 is mounted to travel over two sprockets 97 mounted on shafts 98 and 99 on the frame of the machine. The shaft 98 carries a sprocket 100 connected by sprocket chain 101 with a sprocket 102 on a shaft 103. As best shown 15 in Figs. 4, 6 and 7 the sprocket 102 carries a bevelled gear 104 meshing with a bevelled gear 105 on a shaft 106 carrying a gear 107 meshing with an idler gear 108 meshing with gear 36 and whereby said endless belt conveyer will be constantly operated to discharge the bottles from the machine.

By this arrangement it will be noted that the bottles placed upon the feeding rack will be automatically inverted and placed in the 25 machine, carried through the machine and automatically uprighted and discharged therefrom.

A suitable hood 109 is arranged over the remaining portion of the machine including 30 the sprocket 17 and through which the bottles or other articles thus fed into the machine are carried during the normal operation thereof. Obviously suitable washing elements may be arranged in said hood for 35 spraying the bottles inside and out and thus cleansing the same. The present invention has no relation to the specific form and arrangement of washing mechanism employed, any suitable desired arrangement for this 40 purpose being employed. Such arrangement is illustrated in the co-pending application of Harry D. Lathrop, one of the applicants herein and filed May 31, 1921, Serial No. 473,677, and needs no further description 45 here as no claim is made herein to any specific form of washing mechanism. It might also be added that if desired the bottles or other articles carried by the present machine may be subjected to other treatments than washing, for instance, they might be filled or otherwise treated, and we therefore do not illustrate the specific mechanism 50 for treating the bottles during their travel on the machine, the present invention relating solely to the means for carrying the bottles or other articles treated; the means for automatically feeding the bottles or other articles thereto and the means for automatically discharging the bottles or other articles 55 therefrom. The treatment to which the bottles or other articles are subjected during their handling by this machine is optional and may be varied if desired.

60 While we have illustrated and described the preferred form of construction for car-

rying our invention into effect, this is capable of variation and modification without departing from the spirit of the invention. We, therefore, do not wish to be limited to the precise details of construction set forth, 70 but desire to avail ourselves of such variations and modifications as come within the scope of the appended claims.

Having described our invention, what we claim as new and desire to secure by Letters Patent is:

1. A machine of the class described comprising a travelling conveyer; a plurality of article holders mounted on said conveyer to tilt relatively thereto and independently thereof; means at one location for automatically tilting said holders to receive articles; and a tilting rack at said location for automatically depositing articles in said tilted holders, substantially as described. 80

2. A machine of the class described comprising a travelling conveyer; a plurality of article holders mounted on said conveyer to tilt relatively thereto and independently thereof; means at one location for automatically tilting said holders to receive articles; a tilting rack at said location for automatically depositing articles in said tilted holders; means at another location for automatically tilting said holders into discharging positions; and a tilting rack at said other location for automatically receiving said discharged articles, substantially as described. 90

3. A machine of the class described comprising a travelling conveyer; article holders pivoted on said conveyer; rollers on said holders; a guide track for said rollers; means for moving a portion of said track to tilt the holders thereon; and means for automatically depositing articles in said holders when tilted, substantially as described. 100

4. A machine of the class described comprising a travelling conveyer; article holders pivoted on said conveyer; rollers on said holders; a guide track for said rollers; means for moving a portion of said track to tilt the holders thereon; a tilting rack for holding articles; and means for tilting said rack simultaneously with said 110 holders to discharge said articles into said holders, substantially as described. 115

5. A machine of the class described comprising a travelling conveyer; article holders pivoted on said conveyer; rollers on said 120 holders; a guide track for said rollers; means for moving a portion of said track to tilt the holders thereon into discharging positions; and means for receiving articles discharged from said holders, substantially 125 as described.

6. A machine of the class described comprising a travelling conveyer; article holders pivoted on said conveyer; rollers on said 130 holders; a guide track for said rollers;

means for moving a portion of said track to tilt the holders thereon into discharging positions; a tilting rack arranged to receive articles discharged from said holders; and 5 means for tilting said rack to discharge articles therefrom, substantially as described.

7. A machine of the class described comprising a travelling conveyer; article holders pivoted on said conveyer; rollers on said holders; a guide track for said rollers; means for moving two separated portions of said track to tilt the holders thereon; means for automatically depositing articles 10 in one set of said holders when tilted; and means for automatically receiving and discharging articles delivered from the other set of holders when tilted, substantially as described.

20 8. A machine of the class described comprising a travelling conveyer; article holders pivoted on said conveyer; rollers on said holders; guide tracks for said rollers; means for moving separated portions of said tracks 25 to tilt the holders thereon; a tilting rack adjacent one of said portions of said track for holding articles; means for tilting said rack simultaneously with the adjacent holders to discharge said articles into said holders; a tilting rack for holding articles arranged adjacent said other portion of said track to receive articles discharged from the adjacent holders; and means for tilting said last mentioned rack to discharge articles 30 therefrom, substantially as described.

35 9. A machine of the class described comprising a horizontally driven endless belt conveyer; article holders pivoted on the outer side of said conveyer to project outwardly therefrom; rollers on the outer sides of said holders; a guide track for said rollers, said guide track being provided with two depressible portions on opposite sides of said conveyer arranged to cause downward and outward tilting of said holders when depressed; and means for automatically depositing articles in one set of tilted 40 holders and removing articles discharged from the other set of tilted holders, substantially as described.

45 10. A machine of the class described comprising a horizontally driven endless belt conveyer; article holders pivoted on the outer side of said conveyer to project outwardly therefrom; rollers on the outer sides of said holders; a guide track for said rollers, said guide track being provided with two depressible portions on opposite sides of said conveyer arranged to cause downward and outward tilting of said holders when depressed; a tilting rack arranged adjacent one depressible portion of said track and adapted to receive a plurality of articles in substantially upright positions; means 50 for tilting said rack simultaneously with the

tilting of the holders to invert and deposit said articles in said holders; and means for receiving articles discharged by the tilting of the holders on the opposite depressible track portion, substantially as described.

55 11. A machine of the class described comprising a horizontally driven endless belt conveyer; article holders pivoted on the outer side of said conveyer to project outwardly therefrom; rollers on the outer sides of said holders; a guide track for said holders; said guide track being provided with two depressible portions on opposite sides of said conveyer arranged to cause downward and outward tilting of said holders when depressed; a tilting rack arranged adjacent one depressible portion of said track and adapted to receive a plurality of articles in substantially upright positions; means for tilting said rack simultaneously with the 60 tilting of the holders to invert and deposit said articles in said holders; a tiltable rack arranged to receive articles discharged from the holders on the opposite depressible track portion; a driven conveyer adjacent said last mentioned tiltable rack; and means for tilting said last mentioned rack to upright said articles and deposit the same on said conveyer, substantially as described.

65 12. A machine of the class described comprising two horizontally rotating sprocket wheels; a sprocket chain mounted on said wheels to travel in a substantially horizontal plane; article holders pivoted on the outer side of said chain to swing downwardly and outwardly, said article holders being open at the top and bottom; rollers on the outer sides of said holders; a guide track for said rollers surrounding said chain, said guide track being provided with two depressible sections on opposite sides of said chain; two horizontal rocking shafts arranged under said chain; operating gears on said shafts; vertically reciprocating rack bars meshing with said gears for simultaneously operating said shafts in opposite directions; means for intermittently operating said sprocket wheels to cause intermittent feeding of said chain; means for operating said rack bars to operate said shafts during pauses in the travel of said chain; rocker arms on said shafts; links connecting said rocker arms with said depressible track portions; a tiltable rack arranged adjacent one of said track portions to receive a plurality of articles in substantially upright positions and tilt into registration with the adjacent holders to invert and discharge said articles thereinto; rocker arms on said rocker shafts operatively connected with said rack to effect operations thereof; and means for receiving articles discharged from the holders resting on the opposite depressible track portion, substantially as described.

70 13. A machine of the class described com- 120 p- 125 p- 130 p-

- prising two horizontally rotating sprocket wheels; a sprocket chain mounted on said wheels to travel in a substantially horizontal plane; article holders pivoted on the outer side of said chain to swing downwardly and outwardly, said article holders being opened at the top and bottom; rollers on the outer side of said holders; a guide track for said rollers surrounding said chain, said guide track being provided with two depressible sections on opposite sides of said chain; two horizontal rocking shafts arranged under said chain; operating gears on said shafts; vertically reciprocating rack bars meshing with said gears for simultaneously operating said shafts in opposite directions; means for intermittently operating said sprocket wheels to cause intermittent feeding of said chain; means for operating said rack bars to operate said shafts during pauses in the travel of said chain; rocker arms on said shafts; links connecting said rocker arms with said depressible track portions; a tilttable rack arranged adjacent one of said track portions to receive a plurality of articles in substantially upright positions and tilt into registration with the adjacent holders to invert and discharge said articles thereinto; rocker arms on said rocker shafts operatively connected with said rack to effect operations thereof; a tilttable rack adjacent said opposite depressible track portion and arranged to receive articles discharged from holders thereon in substantially prone positions; rocker arms on one of said rocker shafts operatively connected with said discharging rack to tilt the same to upright said articles and discharge them; and a travelling conveyer arranged to receive articles discharged from said last mentioned rack, substantially as described.
14. A machine of the class described comprising two horizontally rotating sprocket wheels; a sprocket chain mounted on said wheels to travel in a substantially horizontal plane; article holders pivoted on the outer side of said chain to swing downwardly and outwardly, said article holders being open at the top and bottom; rollers on the outer sides of said holders; a guide track for said rollers surrounding said chain, said guide track being provided with two depressible sections on opposite sides of said chain; two horizontal rocking shafts arranged under said chain; operating gears on said shafts; vertically reciprocating rack bars meshing with said gears for simultaneously operating said shafts in opposite directions; means for intermittently operating said sprocket wheels to cause intermittent feeding of said chain; means for operating said rack bars to operate said shafts during pauses in the travel of said chain; rocker arms on said shafts; links connecting said rocker arms with said depressible track portions; a tilttable rack arranged adjacent one of said track portions to receive a plurality of articles in substantially upright positions and tilt into registration with the adjacent holders to invert and discharge said articles thereinto; rocker arms on said rocker shafts operatively connected with said rack to effect operations thereof; a tilttable rack adjacent said opposite depressible track portion and arranged to receive articles discharged from holders thereon in substantially prone positions; rocker arms on one of said rocker shafts operatively connected with said discharging rack to tilt the same to upright said articles and discharge them; and a travelling conveyer arranged to receive articles discharged from said last mentioned rack, substantially as described.
15. A feeding device comprising a tilttable rack provided with a plurality of V-shaped recesses and a supporting ledge at the bottom of said recesses arranged and adapted to receive and support a plurality of bottles or the like in substantially upright positions; and means for tilting said rack to reverse and discharge said bottles, substantially as described.
16. A feeding device comprising a tilttable rack provided with a plurality of V-shaped recesses and a supporting ledge at the bottom of said recesses arranged and adapted to receive and support a plurality of bottles or the like in substantially upright positions; a rocker shaft; rocker arms on said shaft; links connecting said rocker arms with said rack; and means for operating said rocker shaft to tilt said rack to reverse and discharge said bottles, substantially as described.

In testimony whereof we have signed our names to this specification.

HARRY D. LATHROP.
WALTER H. PAULSON.
